United States Patent Office

Des. 183,688
Patented Oct. 14, 1958

183,688

AUTOMOBILE GRILLE UNIT OR THE LIKE

Edward E. Glowacke, Birmingham, Mich., assignor to General Motors Corporation, Detroit, Mich., a corporation of Delaware

Application May 5, 1958, Serial No. 50,753

Term of patent 7 years

(Cl. D54—2)

Fig. 1

Fig. 2

Figure 1 is a front elevational view of an automobile grille unit or the like, showing my new design;

I claim:

The ornamental design for an automobile grille unit or the like, substantially as shown.
